MOLD FOR GLASSWARE

1,331,471.

Specification of Letters Patent.

Patented Feb. 17, 1920.

Application filed March 26, 1915. Serial No. 17,181.

To all whom it may concern:

Be it known that we, KARL E. PEILER and WILLIAM A. LORENZ, citizens of the United States, residing at Hartford, in the county of Hartford and State of Connecticut, have invented new and useful Improvements in Molds for Glassware, of which the following is a specification.

This invention is an improved sectional mold for use in the shaping of glassware, the improvements enabling the mold to be opened and closed, locked and unlocked, all by one hand of the operator, leaving his other hand free to remove the glassware, or for any other purpose.

While the invention is applicable to other uses, it is herein shown and described as being especially adapted for use in a manually operated or semi-automatic glass blowing machine. Molds of this class employed for the shaping of glassware which is of a necked or shouldered form so that it cannot be ejected endwise from the mold, are commonly termed sectional molds, being made in separable sections, usually hinged together at one side to open on the other side. These molds must be clamped firmly together in their closed position while the glass is being blown or otherwise shaped in the mold cavity or matrix formed in the abutting sides of the mold. After the ware has set the sections are unclamped and swung open to enable the ware to be removed. It is usually necessary to swing both of the sections away from their central closed position, so as to give easy access to the ware, and to enable it to be lifted out without striking the sides of the mold. In the use of hand operated molds of this class, it has been necessary for the operator to use both hands for the unlocking and opening of the mold sections, while holding in one hand tongs or other implements which are then used for removing the ware, after which both hands must again be used for closing together and clamping the sections, in readiness for the next succeeding shaping operation.

In the present invention the mold sections, which are preferably hinged together on a vertical pin to swing horizontally, are also connected together by means which cause the sections to participate in their swinging movements, all sections being thus moved in response to one hand of the opera-

tor applied to any of them. Preferably each movement is equalized between the sections, or in other words, is imparted equally to each of them, since it is usually necessary to open all sections to an equal extent from their closed position, leaving the pressed ware centrally between them to allow its free removal.

The invention also provides for clamping the mold sections firmly together and unclamping them by the same single hand employed for opening and closing them, the clamping movement being a continuation of the closing movement, and the opening movement being a continuation of the unclamping movement of the hand.

The invention also includes means for controlling and guiding the clamping device, preventing it from being operated inadvertently or otherwise except at the closed-together position of the mold sections.

Figure 1 of the drawing is a plan view showing one embodiment of the invention, the sections being shown in open position. Fig. 2 is a side elevation partly in section taken through the longitudinal center of the apparatus when the sections are in their closed position. Fig. 3 is a side elevation partly in section, showing a modified construction of the centering base member of the mold. Fig. 4 is a fragmentary plan view in section taken through the clamping arm. Fig. 5 is a plan view and Fig. 6 a side elevation of a modified construction of the apparatus, showing a geared connection between the sections instead of the linkage connection of Figs. 1 and 2. Fig. 7 is a side elevation, showing the operating handle in its raised position.

The apparatus of Figs. 1 and 2 is mounted upon a base plate 5 carrying a vertical hinge stud 6 for the mold sections 7 and 8; and also carrying a hinge stud 9 for the link arm 10. The sections, herein shown to be two in number, are disposed and connected so as to close together on opposite sides of the centering base 11, which may be made integrally with the base plate 5, as shown in Fig. 2, or be made a separate piece 12, removable secured to the base plate 5, as shown in Fig. 3. The latter construction enables the centering piece to be renewed or changed, maintaining its central position. When the mold sections are closed, the top

surface of the base forms the bottom of the mold cavity or matrix, half of which is recessed at 13 and 14 into the mold sections 7 and 8, respectively. The bases are preferably provided with an undercut annular ledge 15, fitting corresponding recesses in the mold sections when the latter are closed, thus tending to hold the sections firmly down upon the base plate 5 when they are 10 clamped together around the base.

The mold sections are provided with the bosses 20 and 21, which are connected by links 22 and 23 and pivot pins 25, with the pivot pin 24 carried at the end of the link arm 10, which serves as a swinging guide for the pin 24, and for the adjacent ends of the links 22 and 23, thereby controlling the relative closing movements of the mold sections, and substantially equalizing those 20 movements. The connecting pins and studs are preferably made removable so that the parts may be easily and quickly assembled and disassembled. This link connection enables the mold sections to be opened or 25 closed concurrently by the movement of either of them. Each operates on the other through their connection, which compels concurrence of movement. A stop pin 26 may be employed to limit their opening 30 movement, which would be sufficient to enable the piece of finished glassware left standing upon the base 11 to be readily lifted away by means of tongs or other suitable appliances.

An operating handle 30 is hinged upon the stud 31 carried by a lug 32 on either of the sections, in this case the section 7. This handle serves the double function of opening and closing the mold sections, and of 40 clamping them firmly together when closed. For its clamping function the handle is pivoted as above described, and is provided with clamping arms 33 and 34, best shown in section in Fig. 4, having beveled inner 45 faces which engage the opposite outer sides of the lugs 35 and 36, projecting from the outer swinging ends of the mold sections. The movements of the mold sections to their closed position, brings the lugs 35 and 50 36 together inside of the clamping arms of the handle, which is then swung downwardly to its clamping position shown in Figs. 2 and 4. A suitable amount of end play of the handle 30 on its hinge stud 31 is allowed to permit the mold sections to 55 center themselves by the base piece 11, instead of being determined by the position of the handle, which by sliding lengthwise upon the stud 31 is accommodated to the 60 centered position of the mold sections. Thus the strain of clamping the sections together is applied close to the matrix, by direct connection through the solid one piece clamp arms, without employing or 65 acting upon any linkage or toggle devices,

the flexibility of which would lessen the firmness of the grip. For convenience and compactness the outer portion 37 of the handle may be made to unscrew from its pivoted and clamping portion, as shown in Fig. 2.

Means are provided for holding the handle in its raised, unclamped position, shown in Fig. 7, and by dot-and-dash lines in Fig. 2, during and preferably throughout its 75 swinging movement, thus holding the clamping arms 33 and 34 clear of the clamping lugs 35 and 36. For this purpose, the handle is provided with an arm 40, the end of which rests against the arc shaped guide 80 41 at the edge of the base plate 5. Arriving at its closed position, the arm 40 clears its guiding surface 41 and enters the clearance slot 42 in the base plate 5, allowing the handle to be swung downwardly to clamp 85 the sections together.

A stop 43 for the upward, unclamping movement of the handle, best shown in Figs. 1 and 7, abuts against the mold section when the arm 40 is withdrawn from the slot 90 42 far enough to clear the guide 41 and thus permit the horizontal movement of the handle to open the sections. This enables the operator to determine promptly, by the sense of feeling, when the sections are fully 95 unclamped.

The operating handle 30 may be mounted upon either of the sections 7 or 8, the choice depending somewhat upon the type of the machine with which the apparatus is employed, or the direction of movement, if used 100 while traveling, or upon other conditions.

This apparatus is well adapted for use with a rotary machine, having a revolving horizontal table carrying a number of these 105 molds, which are operated in succession as they pass by the operator, who, with one hand unclamps and opens the mold, then closes and reclamps it, meanwhile removing the glassware with tongs held in his 110 other hand. It has heretofore been necessary in hand operated machines, for the operator to use both hands for opening and closing the mold, letting go with one hand, while using tongs to remove the pressed 115 ware, then grasping the handle again with that hand to assist the other hand in closing and clamping the mold in readiness for receiving the next blank. The adaptability of the present mold to be unclamped, 120 opened, closed and reclamped, with one hand, without letting go of the operating handle, enables the work to be much more easily, and quickly performed, with less liability of failure, or accident.

Although the mold may be thus operated by one hand, it may be found convenient to provide a fixed handle 45 for the other mated section, especially when the apparatus travels in the same direction as the 130

closing movement of the handle. If for example, as now frequently happens, the operator should be delayed in removing the glassware, because of sticking or for any other reason, he might not have time to close the mold again by pushing the operating handle 30 forward in the direction of travel of the machine. In that case, either the operator or the transfer boy could merely by holding back the fixed handle 45, close the sections together, which would then be locked by falling movement of the operating handle 30, supplemented if need be by a tap from the hand of the operator, or of the transfer boy when it reaches him. All of this, however, requires only a single hand of the operator, due to the circumstance that the sections are connected so that either section when moved will concurrently move the other section.

In the modifications shown in Figs. 5 and 6, the sections 48 and 49 are pivoted upon a hinge pin 50, as in the previous figures, but are connected by gearing instead of by linkage. The gear 53 is secured to a downwardly projecting hub 54 of the mold section 49, while the gear 51 is similarly secured to the arm 52 of the other mold section 48. The first gear 51 meshes with the intermediate gear 56 on the pivot stud 57, while the gear 53 meshes with another intermediate gear 58 on the pivot stud 59, these studs, as well as the hinge stud 50, being carried by the base plate 60. The intermediate gears 56 and 58 mesh together as shown in Fig. 5. This double intermediate connection with the gears 51 and 53 causes them to move in opposite directions when moved by the opening or closing of either of the sections, which thus operates through this geared connection to open and close the sections concurrently as in the arrangement already described in connection with the preceding figures.

The operating and clamping devices of this modified arrangement are or may be like those already described in connection with Figs. 1 and 2, and hence need no specific description here.

The movements of the operating handle, horizontally with the mold section, and vertically on the mold section, describe an approximately L-shaped path, along which the operator moves his hand back and forth, changing the direction of movement when stopped at the angle. From its unvarying guided repetition, this movement soon be-

comes wholly mechanical without conscious guidance or attention on the part of the operator, who is thus left free to devote his entire attention to the other operations and other conditions of the machine.

We claim as our invention:—

1. The combination, with a sectional mold for glassware, of a clamping device for clamping the sections in their closed position, an operating handle for the clamping device mounted on one of the sections to move in a direction different from that of the opening and closing movement of its section, and a guide adjacent to the path of opening and closing movement of the clamping device for preventing its clamping movement at open positions of the sections.

2. The combination, with a sectional mold for glassware, having sections mounted for swinging movement to and from their closed position, a clamping device for clamping the sections at their closed position, including an operating handle mounted upon one of the sections for swinging movement upon an axis different from that of the swinging sections, and means for controlling the movements of the clamping device to prevent its clamping movement during the swinging movement of the sections.

3. The combination, with a sectional mold having mold sections mounted for horizontal swinging movement, a lever mounted on one of the sections for vertical swinging movement, and provided with means for clamping the sections together at their closed position, and a guide engaging with the clamping device to prevent its clamping movement otherwise than at the closed position of the sections.

4. The combination, in a mold for glassware, of a base, mold sections mounted upon the base for swinging movement, a clamping device for the sections mounted upon one of them for swinging movement, for clamping the sections together at their closed position, and a control member engaging with the base, the base being adapted to control the swinging movement of the clamping device during the closing movements of the sections, whereby the clamping device is prevented from interfering with the said closing movement.

In testimony whereof we have signed our names to this specification.
